APPARATUS FOR HYDROTHERAPY

Alpha C. Solley, Jersey City, N. J., assignor of
one-half to Joseph Hanchrow, New Rochelle,
N. Y.

Application September 5, 1934, Serial No. 742,708

14 Claims. (Cl. 128—370)

This invention relates to apparatus for hydro-therapy, and more particularly a whirlpool arm and leg bath.

The whirlpool arm and leg bath has proved effective in the treatment of a variety of conditions such as arthritis, neuritis, old fractures, stiff joints, ulcerations, rheumatic conditions, and for the loosening of scar tissue and adhesions. The treatment is effective, however, only by the use of 5 large quantities of hot water directed forcibly under high pressure against the part undergoing treatment. The prevalent practice is to supply hot and cold water through a special thermostatic mixer which attempts to maintain the 10 desired constant temperature, and from which the water is supplied to a nozzle immersed in the bath or tank where it is ejected against the part undergoing treatment. The water overflows and drains near the top of the tank and is then discarded.

A primary object of my invention is to generally improve apparatus of this class. More particular objects of my invention are to avoid the large waste of water which takes place in the 15 foregoing apparatus and to maintain a constant temperature, while using large quantities of water at high pressure; to make treatment possible even where no running water is available; to make possible the use of solutions; and to make 20 the apparatus portable so that it may be moved to the patient. These and other objects are fulfilled generally by the use of a circulating system in which the liquid is drained from the tank and pumped at high pressure back into a water 25 discharge nozzle in the tank.

It has been proposed to use a centrifugal pump immersed directly in the tank, but in accordance with further features and objects of my invention, the liquid is circulated by the use of a gear 30 pump located externally of and preferably somewhat remote from the tank. I find that a gear pump may be effectively used for the circulation of a large quantity of water at a high pressure, say fifty pounds per square inch. This pressure 35 is unobtainable with a centrifugal pump, and experience indicates that the use of low pressure circulation is not effective therapeutically.

Further objects of my invention are to facilitate filling and draining the tank so that it will 40 not be necessary to move the same when filled with liquid, nor to provide a special plumbing system, the pump being utilizable to drain the tank at a higher elevation, for example into a sink; to make possible electrical insulation of the entire 45 apparatus so that treatment by hydro-therapy

may, if desired, be combined with electrical therapy; and to improve the construction of the aerating water discharge nozzle.

To the accomplishment of the foregoing and other objects which will hereinafter appear, my invention consists in the apparatus for hydro-therapy and the parts thereof as well as their relation one to the other as hereinafter are more particularly described in the specification and sought to be defined in the claims. The specification is accompanied by a drawing, in which:

Fig. 1 is a perspective view showing apparatus embodying features of my invention; and

Fig. 2 is an enlarged section showing some of the details thereof.

Referring to the drawing, and more particularly to Fig. 1 thereof, the apparatus comprises a bath or tank 12, a gear pump 14 located externally of tank 12 and preferably somewhat removed therefrom, a motor 16 for driving pump 14, a discharge nozzle system generally designated 18, and appropriate piping or hose connecting pump 14 with tank 12 and nozzle 18 to form a circulating system. Specifically, I prefer to employ flexible rubber hose, one length 20 being connected between the bottom of tank 12 and the inlet of pump 14, and another length 22 being connected between the outlet of pump 14 and the upper end of the vertical water supply pipe 24. Tank 12 is filled with liquid 26, ordinarily hot water, to any desired level depending upon the part of the body being treated. The temperature of the water may be regulated to exactly the desired temperature by simply suspending a suitable thermometer 28 in the liquid 25 and adjusting the temperature to the desired amount by the addition of hot or cold water as may prove appropriate. The liquid may be circulated by pump 14 during the adjustment of temperature. I find from practical experience that the temperature of the water does not change appreciably during the treatment, the total change being a matter of only one or two degrees F. It is obvious that a solution, as of Epsom salt 30 or an antiseptic solution, may be used to any desired concentration because the liquid is recirculated instead of being discarded.

I preferably provide a pipe or hose 30 in addition to the circulating system, which hose is tapped into the circulating system through an appropriate valve 32. In the present case, I show hose 30 connected at the outlet of pump 14, and valve 32 is adapted to direct the water discharged from the pump into either hose 22 or hose 30. With this construction, the tank 35

12 is readily drained before moving the same by merely shifting valve 32 to direct the pump discharge into hose 30, the end of which may be held in an ordinary sink. The hose 30 is valuable 5 not only as a drain pipe, but also to help fill tank 12, for it may be connected to an ordinary sink faucet from which the tank may be filled without operating pump 14, the elevation of the faucet and the ordinary faucet pressure being 10 ample for this purpose.

Pump 14 is preferably insulated from driving motor 16 as by the use of an insulation coupling 34. Pump 14 is itself preferably insulated against grounding as by the use of insulation 36 there- 15 beneath. Similarly, tank 12 is preferably kept ground-free as by being rested upon a dry hard-wood floor 38. With this arrangement and with drain pipe 30 removed from the faucet or sink, the entire system is kept ground-free and is 20 therefore suitable for use in electrical therapy. More specifically, the liquid 26, preferably a saline solution, is used as one electrode in the treat- 25 ment, the patient preferably sitting or resting upon the other electrode. In this manner, elec- trical therapy may be combined with hydro- 30 therapy, something which is not done with the ordinary non-circulating or overflow drain system, for such a system can not be kept ground-free. Even a circulating system can not 35 be kept ground-free if the pump and motor are mounted directly on or in the tank, because it is difficult to avoid some splashing or accidental contact with the motor.

I have not shown gear pump 14 in detail be- 35 cause it may be substantially conventional in construction. However, I may explain that I prefer the use of fibre gears to the use of metal, and I further prefer the use of herringbone gear teeth to the use of simple spur gear teeth, be- 40 cause of the smooth, silent operation obtainable by these precautions. If desired, the patient may be further guarded against the distraction of noise by removing the pump a substantial dis- tance from the tank, the pump and tank being 45 placed, for example, in different rooms. The pump should be capable of delivering an ample supply of water at a relatively high pressure, at least thirty and more, preferably fifty, pounds per square inch.

50 The discharge nozzle system 18 is shown in greater detail in Fig. 2. I may explain that the liquid is forcibly discharged through a small-dia- 55 meter horizontal discharge nozzle 40, this nozzle being connected to vertical water supply pipe 26 by means of an elbow 42. Air is provided through a vertical air pipe 44 arranged adjacent the water supply pipe 26. The lower end of air pipe 44 surrounds discharge nozzle 40. More speci- 60 cifically, air pipe 44 is connected to a T-fitting 46 which is threaded on to elbow 42 around nozzle 40 and which is itself provided with a large-dia- 65 meter discharge nozzle 48 which surrounds small-diameter water discharge nozzle 40, but which projects further than nozzle 40. The dis- charge of water at high velocity from nozzle 40 creates a suction which draws air downwardly through pipe 44 so that it is a mixture of water and air which is discharged from the nozzle as- 70 sembly.

75 The nozzle assembly may be adjusted to any desired height within the tank and this is preferably accomplished by clamping water supply pipe 26 in a clamp 50 which is secured to an edge of tank 12 as by the use of a spring hook 52. Clamp 50 may be tightened or released by a wing

screw 54, thus facilitating movement of vertical pipe 26 in clamp 50 until the nozzle is at the desired level. It will be understood that pipe 30 is at least as long as the height of the tank. It will also be understood that air pipe 44 is of similar length so that the open upper end thereof will at all times project above the surface of the liquid in the tank.

It is believed that the mode of constructing and using my improved apparatus for hydro- 10 therapy as well as the many advantages thereof will be apparent from the foregoing detailed de- 15 scription. The temperature and pressure during treatment are maintained perfectly constant, whereas when a mixing valve is used with run- 20 ning water, there are fluctuations in temperature and pressure even in large city hospitals because of variable use of faucets. The apparatus is 25 equally useful whether or not running water is available, as in rural districts. Ample high pres- 30 sure is obtainable regardless of building height, thus avoiding difficulty in the upper floors of tall 35 city buildings. The apparatus is economical in the use of water and in the cost of heating the same. Antiseptic and salt solutions may be used. 40 The apparatus is portable. It may be filled to any desired height instead of being drained only when nearly full. The apparatus eliminates spe- 45 cial plumbing which has heretofore been necessary in order to connect high pressure water sup- 50 ply mains to the tank and in order to drain the large quantity of discarded water. The apparatus is insulated and ground-free and therefore may be combined with electrical therapy. The tank 55 may be moved about when empty and filled or 50 drained after being suitably located. The high pressure developed by the pump makes the treat- 60 ment extremely effective by direct impact, and insures maintenance of the entire body of liquid at the same temperature because of the extreme 65 and desirable resulting agitation of the bath.

It will be apparent that while I have shown and described my invention in a preferred form, many changes and modifications may be made in the structure disclosed without departing from the spirit of the invention defined in the follow- 70 ing claims.

I claim:

1. A portable apparatus for hydro-therapy comprising a portable tank, a high pressure pump 50 externally located with reference to said tank, said pump being designed to develop a pressure of the order of 50 pounds per square inch, a motor to drive said pump, a discharge nozzle in the tank provided with means to aerate liquid dis- 55 charged therefrom, said nozzle being so designed as to cause forceful ejection of a stream of water therefrom, flexible hose connecting the pump outlet to said nozzle and the pump inlet to the bottom of said tank, a valve at the pump outlet, and a drain pipe connected to said valve, said valve being so arranged as to direct the water dis- 60 charged from the pump to either the nozzle or the drain pipe.

2. A portable apparatus for hydro-therapy comprising a portable tank, a high pressure pump externally located with reference to said tank, a motor to drive said pump, a discharge nozzle, said nozzle being so designed as to cause forceful ejection of a stream of water therefrom, hose con- 70 necting the pump outlet to said nozzle and the pump inlet to the bottom of said tank, a valve at the pump outlet, and a drain pipe connected to said valve, said valve being so arranged as to direct the water discharged from the pump to 75

either the nozzle or the drain pipe, said pump being a gear pump having fibre gears and adapted to discharge a large quantity of water at a relatively high pressure of the order of 50 pounds per square inch.

5. A portable apparatus for hydro-therapy comprising a portable tank, a high pressure pump externally located with reference to said tank, said pump being designed to develop a pressure of 10 the order of 50 pounds per square inch, a motor to drive said pump, a discharge nozzle in the tank provided with means to aerate liquid discharged therefrom, said nozzle being so designed as to cause forceful ejection of a stream of water therefrom, hose connecting the pump outlet to said nozzle and the pump inlet to the bottom of said tank, a valve at the pump outlet, a drain pipe connected to said valve, said valve being so arranged as to direct the water discharged from the 15 pump to either the nozzle or the drain pipe, and means electrically insulating the driving motor from the pump and insulating the pump and the tank from ground, whereby said tank may be safely employed as one electrode in electrical 20 therapy.

4. Apparatus for hydro-therapy comprising a tank, a pump externally located with reference to said tank, a motor to drive said pump, a discharge nozzle in the tank, hose connecting the 25 pump outlet to said nozzle and the pump inlet to the bottom of said tank, a valve at the pump outlet, and a drain pipe connected to said valve, said valve being so arranged as to direct the water discharged from the pump to either the nozzle or the drain pipe, and the drain pipe said pump being a gear pump having fibre gears and designed to discharge a large quantity of water at a relatively high pressure of, say, 50 pounds per square inch, and means electrically insulating the driving motor from the 30 pump and insulating the pump and the tank from ground, whereby said tank may be safely employed as one electrode in electrical therapy.

5. Apparatus for hydro-therapy comprising a tank, a horizontally directed discharge nozzle, 35 said nozzle being so designed as to cause forceful ejection of a stream of water therefrom, a vertical supply pipe at the lower end of which said nozzle is mounted, a vertical air pipe arranged near said supply pipe and having its lower end surrounding the discharge nozzle, said supply and air pipes being longer than the height of the tank, a clamp 40 mounted at one edge of said tank for holding said supply pipe, and means for tightening or loosening said clamp in order to permit adjustment of the height of the discharge nozzle within the tank.

55 6. Apparatus for hydro-therapy comprising a tank, a horizontally directed small-diameter discharge nozzle, said nozzle being so designed as to cause forceful ejection of a stream of water therefrom, a vertical supply pipe at the lower end of which said nozzle is mounted, a vertical air pipe arranged near said supply pipe and having at its lower end a large-diameter nozzle surrounding the small-diameter discharge nozzle but projecting further than the same, said supply and air pipes being longer than the height of the tank, a clamp 60 mounted at one edge of said tank for holding said supply pipe, and means for tightening or loosening said clamp in order to permit adjustment of the height of the discharge nozzle within the tank.

70 7. A portable apparatus for hydro-therapy, comprising an open-topped portable tank of liquid, a high pressure pump, said pump being designed to develop a pressure of the order of 50

5 pounds per square inch, a motor to drive said pump, a discharge nozzle in the tank provided with means to aerate liquid discharged therefrom, said nozzle being so designed as to cause forceful ejection of a jet of liquid therefrom into the tank, means connecting the pump outlet to the nozzle, means connecting the pump inlet to the liquid in the tank, a valve controlling the liquid discharged from the pump outlet, and a drain pipe for emptying the tank, said valve being so arranged as to direct the water discharged from the pump to either the jet or the drain pipe.

8. A portable apparatus for hydro-therapy, comprising a portable open-topped tank of liquid, a high pressure pump, a motor to drive said pump, a discharge nozzle in said tank, said nozzle being so designed as to cause forceful ejection of a jet of liquid therefrom into the tank, means connecting the pump outlet to said nozzle and the pump inlet to the liquid in the tank, a valve controlling the liquid discharged from the pump outlet, and a drain pipe for emptying the tank, said valve being so arranged as to direct the liquid discharged from the pump to either the jet or the drain pipe, said pump being a gear pump adapted to discharge a large quantity of liquid at a relatively high pressure of 50 pounds per square inch.

9. Apparatus for hydro-therapy, comprising a tank, a horizontally directed discharge nozzle in 30 said tank, said nozzle being so designed as to cause forceful ejection of a stream of water therefrom, an upright support member at the lower end of which said nozzle is mounted, a vertical air pipe arranged near said support member and having its lower end open to the jet from the discharge nozzle, said support member and air pipe being of such length that the nozzle may be raised or lowered over a substantial distance between the top and bottom of the tank, holding means 35 mounted at one edge of said tank for holding said support member, and releasable means for clamping said holding means and the support member together in order to afford adjustment of the height of the discharge nozzle within the tank.

40 10. Apparatus for hydro-therapy, comprising a tank, a horizontally directed small-diameter discharge nozzle in said tank, said nozzle being so designed as to cause forceful ejection of a stream of water therefrom, an upright support member at the lower end of which said nozzle is mounted, a vertical air pipe arranged near said support member and having at its lower end a large-diameter nozzle concentric with the small-diameter discharge nozzle but projecting further than the same, said support member and air pipe being of such length that the nozzle may be raised or lowered for a substantial distance in the tank, holding means mounted at one edge of said tank for holding said support member, and releasable 45 means for clamping said holding means and the support member together in order to afford adjustment of the height of the discharge nozzle within the tank.

50 11. A portable apparatus for hydro-therapy, comprising a portable tank of liquid, a high pressure pump, a motor to drive said pump, a horizontally directed small-diameter discharge nozzle in said tank, said nozzle being so designed as to cause forceful ejection of a jet of liquid therefrom into the tank, means connecting the pump outlet to said nozzle and means connecting the pump inlet to the liquid in the tank, a valve for controlling the liquid discharged from the pump outlet, a drain pipe, said valve being so arranged as to di- 55

rect the liquid discharged from the pump to either the jet or the drain pipe, said pump being a gear pump adapted to discharge a large quantity of water at a relatively high pressure of the order of 50 pounds per square inch, an upright support member at the lower end of which said nozzle is mounted, means to aerate the liquid discharged from said nozzle, said means including a large-diameter nozzle coaxial with the small-diameter discharge nozzle, said support member being of such length that the nozzle may be raised or lowered in the liquid in the tank, holding means mounted at one edge of said tank for holding said support member, and releasable means for clamping said holding means and the support member together in order to afford adjustment of the height of the discharge nozzle within the tank.

12. A portable apparatus for hydro-therapy, comprising a portable tank of liquid, a high pressure pump, a motor to drive said pump, a horizontally directed small-diameter discharge nozzle in said tank, said nozzle being so designed as to cause forceful ejection of a stream of liquid therefrom into the tank, means connecting the pump outlet to said nozzle and means connecting the pump inlet to the liquid in the tank, a valve for controlling the liquid discharged from the pump outlet, a drain pipe, said valve being so arranged as to direct the water discharged from the pump to either the jet of the drain pipe, an upright support member at the lower end of which said nozzle is mounted, means to aerate the liquid discharged from said nozzle, said support member being of such length that the nozzle may be raised or lowered in the liquid in the tank, means mounted at one edge of said tank for releasably holding said support member, said means affording adjustment of the height of the discharge nozzle within the tank.

13. A portable apparatus for hydro-therapy, comprising a portable tank of liquid, a high pressure pump, a motor to drive said pump, a hor-

izontally directed small-diameter discharge nozzle in said tank, said nozzle being so designed as to cause forceful ejection of a stream of liquid therefrom into the tank, means connecting the pump outlet to said nozzle and means connecting the pump inlet to the liquid in the tank, a valve for so controlling the liquid discharged from the pump outlet as to send the same to the jet, or to a drain in order to empty the tank, an upright support member at the lower end of which said nozzle is mounted, an upright pipe arranged collateral to said support member and having its lower end communicating with the small-diameter discharge nozzle, said support member and pipe being of such length that the nozzle may be raised or lowered in the liquid in the tank, and means for releasably holding said support member and for affording adjustment of the height of the discharge nozzle within the tank.

14. A portable apparatus for hydro-therapy, comprising a portable tank of liquid, a high pressure pump, a motor to drive said pump, a horizontally directed small-diameter discharge nozzle in said tank, said nozzle being so designed as to cause forceful ejection of a jet of liquid therefrom into the tank, means connecting the pump outlet to said nozzle and means connecting the pump inlet to the liquid in the tank, a valve for so controlling the liquid discharged from said pump outlet as to send the same either to the jet, or to a drain in order to empty the tank, an upright support member at the lower end of which said nozzle is mounted, means to aerate the liquid discharged through said nozzle, said support member being of such length that the nozzle may be raised or lowered in the liquid in the tank, and means at one edge of said tank for holding said support member and for affording adjustment of the height of the discharge nozzle within the tank.

ALPHA C. SOLLEY.
